UNITED STATES PATENT OFFICE

CARL H. BESSE, OF TULSA, OKLAHOMA, ASSIGNOR, BY DIRECT AND MESNE ASSIGNMENTS, TO THE NATIONAL TURNBUCKLE DERRICK COMPANY, OF TULSA, OKLAHOMA, A CORPORATION OF OKLAHOMA

CORNER IRON FOR TUBULAR-STEEL DERRICKS

Application filed March 8, 1927. Serial No. 173,685.

This invention relates to improvements in the units of construction of derricks or towers, such for example, as are used in connection with the drilling, spudding and pumping of oil, gas or artesian wells, the invention having for an object to provide a highly efficient and practicable form of derrick leg bracket or "iron" for positively connecting the abutting ends of derrick leg sections and holding the same in assembled relation, and also, to permit of the operative connection of braces and girths to the derrick legs whereby to rigidify and stabilize the entire construction.

It is also amongst the principal desiderata of the invention to provide a bracket of the character mentioned particularly adaptable for use in connection with reinforced types of derricks, wherein the derrick main legs or leg proper, are equipped with juxtaposed relatively parallel reenforcing legs, adapted to lend sufficient strength to the derrick construction that the same may be safely and efficiently used for well drilling or spudding operations, whereupon, with completion of such operations, the reenforcing legs may be detached and removed, thus leaving standing, a materially lighter construction practicable for use as a pumping derrick, the removed reenforcing legs being completely salvaged for use in the reenforcing (re-legging) of other light pumping derricks.

The invention has for another of its objects to provide a derrick leg bracket or "iron" so constructed that the same may be quickly yet positively connected to the main legs and when desired or required, to the reenforcing legs of a derrick construction at a materially less labor cost and, in addition to serving as a coupling between such legs and the sections of which they are usually composed, will afford means for effecting connection between the legs and the usual braces and girths employed in derrick construction work.

Other objects of the invention will be in part obvious and in part pointed out hereinafter.

In order that the invention and its mode

of operation may be understood by those skilled in the art, I have in the accompanying illustrative drawings and in the detailed following description based thereupon, set out one possible embodiment of the invention.

In these drawings:

Figure 1 is a disassembled perspective of the improved derrick leg bracket,

Figure 2 is a side elevation of the same showing it in usage, that is, connected to the main and reenforcing legs of a derrick construction, and

Figure 3 is a top view of the improved bracket showing it applied to the main and reenforcing legs of a derrick construction.

Having more particular reference to the drawings, in connection with which like characters of reference will designate corresponding parts throughout, the improved bracket may be stated to comprise substantially complementally formed or constructed plates indicated in their entireties by the numerals 1 and 2, said plates each being formed of metal or of other suitable material, cast or molded and having curved or dished derrick leg receiving portions 3 therein longitudinally of themselves, while plane flanges 4 are formed upon the normally outer ends of the plates and are provided with complementally arranged fastening bolt receiving openings 5, the purpose of which will be subsequently described. The inner side portions of the bracket plates 1 and 2 are formed with angularly disposed web like extensions

having complementally arranged bolt receiving openings 7 formed therein while adjacent the upper and lower portions of these web-like extensions 6, curved reenforcing derrick leg arms are formed, the outer faces of said arms being formed with grooves or ways 9 aligned with certain of the bolt receiving openings 7, aforesaid. Also, in this connection, it will be noted that the curved reenforcing derrick leg arms 8 are longitudinally offset with respect to the opposite ends of their particular plates 1 and 2, as is shown in the Figures 1 and 2 and furthermore, that said arms are so positioned upon the webs 6 that with assembly of the bracket plates

100

1 and 2, such arms will be paired in the fashion as is shown in the Figure 3, thus providing a seat or receiving means for portions of the particular reenforcing derrick legs 10 of an equipped derrick.

5 That the bracket plates 1 and 2 may be positively interconnected and permitted of pivotal movement in order that they may be 10 embracingly engaged about the adjacent portions of the main legs 11 of a derrick, one longitudinal portion of the plate 1 is formed with a series of integral and relatively spaced pebble engaging fingers 12, such fingers opening in a direction away from the curved portion 15 15 3 and extended beyond said portion as is well illustrated in the Figures 1 and 3.

Upon a corresponding longitudinal portion of the remaining bracket plate 2, there are formed or cast integral therewith a series 20 of longitudinally arranged and relatively spaced bearing fingers 13 and 14, the respective widths of the bearing fingers 13 corresponding to the spacing between the adjacent ends of certain of the hooked fingers 12 25 so as to permit of their snug introduction or arrangement therebetween. A pivot pin is cast integral with or otherwise suitably and fixedly carried by these bearing fingers 13 and 14.

30 Thus, it will be understood that the bracket plates 1 and 2 may be positively and pivotally interconnected by engaging the hooked fingers 12 over the intermediate portions of the pintle or pivot pin 15, thus allowing of the 35 swinging or pivotal movement of those portions of said plates 1 and 2 having the curved longitudinally disposed portion 3 therein to be embracingly engaged about adjacent portions of the main legs 11 of a derrick construction supplied with the devices.

Connecting or locking bolts indicated by the numeral 16 are, with embracing engagement with the plates 1 and 2 about the main derrick legs, passed through the aligned bolt 45 receiving openings 5 in the flange like extensions 4, whereupon locking nuts 17 are turned into engagement with their screw threaded extremities and thus, serve as a means for effecting the clamping engagement of said 50 plates 1 and 2 upon the main derrick legs 11.

With a view toward providing the derrick leg brackets or "irons" with means for effectually securing the reenforcing legs 10 between the pairs of curved arms 8, substantially U-shaped clamping bolts 18 are passed over portions of the inner sides of such legs 10 and having their screw threaded extremities engaged through certain of the bolt receiving openings 7 in the opposite ends of the web-like extensions 6, following which locking nuts 19 are engaged therewith, as is shown in the Figure 3. In this connection, it is to be noted that the free extremities or shank portions of the U-shaped clamping 65 bolts 18 will be received in the grooves or

ways of the curved reenforcing leg engaging arms 8 and consequently thereupon, that relative longitudinal movement of said bolts with respect to the reenforcing derrick legs will be prevented.

70 In addition to serving as a means for interconnecting the abutting sections of the main derrick legs and as a means for rigidly interconnecting the main derrick legs and the reenforcing derrick legs, it will be understood 75

that my improved derrick leg coupling bracket or "iron" affords effectual means for securing the opposite ends or extremities of the usual derrick braces or trusses and girders thereto, such means being in form of the 80

angularly disposed web-like extensions 6, as is shown in the Figures 2 and 3. These web-like extensions 6, with assembly or interconnection between the bracket plates 1 and 2

will be disposed at substantially right angles to each other and consequently thereupon, in substantially parallelism to certain of the sides of the derrick construction. Thus, it

will be understood that the adjacent ends or portions of the derrick braces or trusses 20 and the girders 21 may be engaged therewith in the fashion as is shown in the Figures 2 and 3; connecting bolts 22 and 23 being passed through the adjacent apertured ends of said

braces and girders and through the adjacent bolt receiving openings 7 in the web like extensions 6. Consequently upon this engagement of the girders and braces with the bracket plates, it will be appreciated that the 90

equipped derrick may be effectually strengthened or rigidified to withstand those stresses to which it will be subjected during usage.

95 As hereinbefore stated, when desiring to use or apply the improved derrick leg brackets to the main legs 11 of a derrick construction, the plates 1 and 2 are pivotally interengaged by engaging the hooked fingers 12 over adjacent portions of the pintle 15 carried by the bearing fingers 13 and 14, following which

100 those portions of said plates having the curved leg receiving portions 3 are embracingly engaged over the main derrick legs and are then clampingly secured to the same by arrangement and connection of the locking bolts 16 and nuts 17 through the openings 5

110 in the flange like extension 4. In this connection, it will be understood that the bracket plates may be employed as a means for efficiently coupling the longitudinally aligned or abutting ends of the main derrick leg sections, being overlappingly engaged with said

115 meeting ends of the derrick leg sections and then clampingly secured to the same through the connecting bolts 16 and their respective locking nuts 17.

120 Also, it will be understood that the bracket plates 1 and 2 may be engaged, not only with the derrick leg sections adjacent their points of jointure, but may engage with such legs at any points through

125

130

out their lengths, such as conditions or preference may dictate.

Having clampingly connected the bracket plates 1 and 2 to the main derrick legs 11, the usual tubular or otherwise formed reenforcing derrick legs 10 are arranged in position, portions of said reenforcing legs being engaged between the curved seats provided therefor in the opposed and paired curved engaging arms 8 as shown in the Figure 3. With the re-enforcing legs 10 so engaged, clamping U-shaped bolts 18 are passed about the same and have their extremities engaged in certain of the openings 7 of the web-like extension 6, following which locking or connecting bolts 19 are engaged therewith. Thus, a positive and bracing connection is established between the main derrick legs and the reenforcing derrick legs through the improved brackets. Furthermore, by reason of the relative right angular disposition of the outer faces of the web-like extensions 6, it will be understood that the adjacent ends of the usual derrick braces or trusses (turn buckle or otherwise) and the derrick girths may be effectually connected thereto through the medium of bolts 22 and 23, thus giving further rigidity and stability to the derrick construction.

Due to the peculiar formation and arrangement of the curved leg engaging arms 8, it will be seen, especially upon reference to the Figure 3, that those portions of the reenforcing legs 10 received between the paired arms will be positioned adjacent the pivotal connection between the plates 1 and 2 afforded by the hooked fingers 12 engaging portions of the pintle 15 carried by the bearing fingers 13 and 14.

Such engagement of the reenforcing legs 10 between the arms 8 will, with the clampingly connection of the U-shaped bolts 18, impart lateral and opposed stresses to the substantially complemental bracket plates 1 and 2 and therefore, it will be understood that undesirable or accidental disengagement of the hooked fingers 12 with the bearing pintle 15 carried in the fingers 13 and 14 will be positively prevented and at the same time, that that portion of the reenforcing leg adjacent to the pivotal connection thus effected will serve as an additional or further locking means.

Subsequently to a drilling or spudding operation, it is desirable that only a light derrick construction be employed, for pumping purposes. To satisfy this desire, the reenforcing legs 10 may be now readily removed or disconnected by disengaging the locking nuts 19 from the screw threaded extremities of the U-shaped clamping bolts 18 and withdrawing said clamping bolts from the openings 7 in the web-like extensions 6. At this time, the derrick reenforcing legs or the sections of which they are composed may be

easily removed from between the seats afforded them through the curved and paired engaging arms 8, thus leaving a light pumping derrick standing upon the operation and also, leaving intact, the bracing connections 20 and 21 with the substantially right angularly opposed outer faces of the web-like extensions 6.

Manifestly, the construction shown is capable of considerable modification and such modification as is within the scope of my claims, I consider within the spirit of my invention.

I claim:

1. A derrick leg bracket comprising a leg receiving body portion, relatively angularly arranged plates integral with and disposed longitudinally of said body portion, and re-leg receiving means integral with the body portion and the opposite ends of said plates, said receiving means being arranged between the plates and in longitudinally opposed relation.

2. A derrick leg bracket comprising a leg receiving body portion, relatively angularly disposed plates integral with and disposed longitudinally of said body portion, and re-leg receiving arms integral with the body portion and the opposite ends of said plates, certain of the sides of said re-leg receiving arms being formed with cradle like portions whereby to receive a re-leg therein.

3. A derrick leg bracket comprising a tubular leg receiving body portion, relatively right angularly arranged plates integral with and disposed longitudinally of said body portion, and re-leg receiving arms disposed transversely of and integral with said body portion and with the opposite ends of said plates, certain of the sides of said arms being formed with cradle like receiving portions disposed between said plates in longitudinally opposed relation.

4. A derrick leg bracket comprising substantially complementally formed leg embracing and clamping plates, means for detachably and pivotally connecting one side of said plates together, means for detachably connecting the opposite sides of said plates, a substantially right angularly disposed brace and girth receiving web like extension formed with each plate in proximity to said means for detachably and pivotally connecting the plates, opposed derrick re-leg engaging arms formed on the extremities of said right angularly disposed web extensions and clamping means connected to said arms whereby the derrick relegs may be detachably connected to said arms.

In witness whereof I have hereunto set my hand.

CARL H. BESSE.
